UNITED STATES PATENT OFFICE

WILLIAM KNOWLTON AND WILLIAM S. VAUGHAN, OF GLEN ELLYN, ILLINOIS

AIR HUMIDIFIER

Application filed April 21, 1930. Serial No. 446,048.

This invention relates to certain novel improvements in air humidifiers.

The principal object of our invention is to provide an air humidifier which will be highly efficient in use and economical in manufacture.

Another object of our invention is to provide a device of this character in which air is taken from the cold air intake of a heating apparatus, suitably compressed and used to force a stream of atomized water into the warm air exits of a heating apparatus.

Another object of our invention is to provide a mechanism of the above named character in which the volume of the compressed air used to atomize the water is automatically adapted to the quantity of atomized water injected into the warm air exits in a heating apparatus.

Still another object of our invention is to provide a humidifier which will permit of convenient humidity control and which will augment the natural draft of a heating apparatus.

Another object is to provide a humidifier which may be adapted to various types of heating apparatus, such as hot air, steam, hot water, and other types of heating apparatus.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is an elevational sectional view of a hot air heating apparatus with our invention adapted thereto; and

Fig. 2 is a view taken substantially on the line 2—2 in Fig. 1 of the water storage tank and showing the manner of mounting the atomizers therein.

Referring to the drawings wherein we have illustrated the preferred embodiment of our invention, 1 indicates a hot air furnace of any approved construction. 2 generically indicates a plurality of hot air exits therefrom and 3 indicates the cold air intake thereto.

Mounted in the cold air intake 3 of the

furnace is an intake for leading into an air compressor 5 operated by an electric motor 6. Controlling the speed of the motor 6 and the air compressor 5 is a movable switch arm 7 which is movable over a row of contacts 8 in circuit with the motor 6 by suitable conductors 9.

The movable switch arm 7 is attached at one end thereof to a bevel gear 10 and suitably insulated therefrom as shown at 11. Mounted so as to be rotated by the gear 10 attached to the movable switch arm 7 is a bevel gear 12. Attached to the gear 12 is a shaft 13 which leads into and controls a valve 14 in a water pipe 15. The pipe 15 leads to a water supply tank 16. Tank 16 has an air vent hole 33 in its upper wall. When the movable switch arm 7 is moved into contact position with the first of the contacts 8 the gear 10 attached to the movable switch arm 7 will rotate the gear 12 and the attached shaft 13 thus partly opening the valve 14 in the water pipe 15 and allowing a controlled flow of water into the water supply tank 16.

Leading from the air compressor 5 is a pipe 17. Mounted on the pipe 17 is a T 18 to which are connected two atomizer air pipes 19 and 20. Mounted in the upper wall of the water storage tank 16 are the body portions of two atomizers 29 and 30. These atomizer bodies may be of the type commonly used in nasal atomizers, although the body portion of any approved type of atomizer that provides an atomized spray sufficiently fine substantially to be buoyed up by a moving current of air may be used. Leading downwardly from the atomizer body portions 29 and 30 into the tank 16 are atomizer supply pipes 21 and 22. Likewise leading from the atomizer body portions 29 and 30 are the vent pipes 31 and 32 of the atomizer structures and these vent pipes 31 and 32 have nozzles 24 and 25 formed in their outer ends. The nozzles 24 and 25 are directed into the hot air chamber of the furnace preferably adjacent the exits thereof.

An over-flow opening 23 is provided in the tank 16.

In the operation of our invention, when the movable switch arm 7 is contacted with

one of the stationary contacts 8, the gear 10 on the arm 7 will rotate gear 12 and shaft 13 so as partially to open the valve 14 thus allowing a determined flow of water into 5 the tank 16 through the inlet pipe 15. This flow of water can, therefore, be conveniently regulated by spacing the contacts 8 and moving the combination switch and valve controlling arm 7. Ordinarily water will flow 10 from the tank 16 to the atomizer 19 through supply pipe 22 under the pressure of compressed air from pipe 17. But when the level of the water in tank 16 reaches the lower end 15 of supply pipe 21 it is apparent that water will flow through pipe 21 into atomizer 20. The atomized water directed through the nozzles 24 and 25 under the pressure of compressed air will flow into the path of the heated air escaping through the warm air 20 exits 2 in the jacket of the furnace. The globules of atomized water directed from nozzles 24 and 25 will be very minute in size and will be buoyed up by the moving current of heated air so as to humidify the heat- 25 ed air without the necessity of previous hot plate or other form of evaporation as has been heretofore necessary in the art.

The fact that air for the compressor is taken in from the cold air intake 3 in the 30 jacket of the heating apparatus while the atomized spray is directed into the path of the hot air leaving the heating apparatus greatly increases the draft of the heating apparatus and improves the function thereof.

35 While we have illustrated and described the preferred form of construction for carrying our invention into effect, this is capable of variation and modification, without departing from the spirit of the invention. We, 40 therefore, do not wish to be limited to the precise details of construction set forth, but desire to avail ourselves of such variations and modifications as come within the scope of the appended claims.

45 Having thus described our invention what we claim as new and desire to protect by Letters Patent is:

1. In combination with a heating apparatus and a jacket surrounding said heating 50 apparatus, said jacket having a cold air intake and a plurality of warm air exits therein, means for withdrawing air from said cold air intake, means for compressing said air, means adapted with said compressed air to 55 atomize water, and means for injecting said compressed air and atomized water into the path of heated air flowing out of said warm air exists in said jacket.

2. In combination with a heating apparatus and a jacket surrounding said heating apparatus, said jacket having a cold air intake and a plurality of warm air exits therein, means for withdrawing air from said cold air intake in said jacket, means for compress- 65 ing said air from said cold air intake, water

storage means connected to said air compressing means, atomizing means in said water storage means, said atomizing means being connected to said air compressing means, said water storage means having an 70 inlet opening therein, supply pipes in said atomizing means and terminating at different levels in said water storage means and being connected with said air compressing means, atomizer vent pipe means connected with 75 said atomizing means, said vent pipes having nozzle means formed therein at one end thereof, said nozzle means being disposed interiorly of said jacket and adapted to spray atomized water into the path of warm air 80 escaping from said heating apparatus, and combination switch and valve means for simultaneously controlling the flow of compressed air and water into said atomizing 85 means.

In testimony whereof we affix our signatures.

WILLIAM S. VAUGHAN.
WILLIAM KNOWLTON.
